UNITED STATES PATENT OFFICE.

OTTO G. LUYTIES, OF SHARON SPRINGS, NEW YORK.

GLOBE FOR STREET-LIGHTING.

1,163,353.

Specification of Letters Patent.

Patented Dec. 7, 1915.

Application filed March 23, 1914. Serial No. 826,626.

To all whom it may concern:

Be it known that I, OTTO G. LUYTIES, a citizen of the United States, and a resident of Sharon Springs, in the county of Schoharie and State of New York, have invented a certain new and useful Globe for Street-Lighting, of which the following is a specification.

This invention relates to globes for street lighting. Its main object is to produce a non-blinding globe of more than usual efficiency.

A further object is to produce a globe which will project an augmented amount of light to one side.

A further object is to produce a non-blinding frosted globe which will project an increased amount of light in a direction slightly below horizontal.

A further object is to produce a globe for street lighting in which the light itself will only be visible to observers who are at some distance from the globe and who will see the light against an illuminated background.

In the drawing Figure 1 shows an elevation of the improved globe and Fig. 2 a vertical section.

This globe is made of glass and is preferably of spherical form, although it is to be understood that other shapes may be employed and that the term "globe" is used in a broad sense to cover any light-transmitting member about a source of light whether permanently associated therewith or removable therefrom.

The globe is translucent except for a transparent band B. The translucency may be produced in any convenient way, preferably by frosting the globe on the inside. The source of light is preferably located at L, a little below the center C of the globe. The transparent band B extends a little more than half way around the globe. This band must be located slightly below the source of light L.

The light thrown by this globe will be somewhat subdued in the manner common to all frosted globes in all directions except the diagonally downward direction LM. In the direction LM this improved globe will project not only as much light as any transparent globe would project but also some additional light refracted and reflected from the wall W through the transparent belt B. The light projected in the

general direction LM will be further augmented by some diffused light from all the frosted portions visible from that direction.

The belt when proportioned approximately as shown will give a greatly increased light at any angle from 5 to 20 degrees below the horizontal, thus illuminating that part of the street between two lamp posts which would otherwise be poorly illuminated. To be effective the band B need only constitute from 5 to 10% of the total area of the globe so that the general effect will be that of a frosted light.

This improved globe may be safely used with a light of high candle-power, because the source of light will only be visible to observers who are looking diagonally upward from a certain considerable distance. Seen in this way the source of light will not be blinding, not only on account of the distance but because, as the inventor has observed, every light appears less blinding when seen against an illuminated background. Furthermore the direct light projected in the general direction LM will be softened by the admixture of a large percentage of diffused light.

The transparent band B is purposely extended only part way around the globe, preferably one half to three quarters of its circumference. By suspending the globe so that the bright band B is turned toward the center of the street this invention will serve to protect residents on the same side as the lamp post from having direct light fall in their windows.

The band R shown in Fig. 1 represents paint applied on the outer surface of the globe along its upper margin. This paint which is optional is preferably white and translucent, and preferably baked on. The action of this paint which serves as a partial reflector is to reduce the light thrown upward and increase the light thrown downward, including some reflected light projected through the transparent band B.

The location of the light L is largely optional. It is preferable to employ a light which will burn in a fairly stationary position within the globe. When L is located slightly below the center of the globe it will project a little more light down than up because the lower half of the globe will be more brightly illuminated. Such location of L will permit a low position of B and permit a large part of the light re-

fracted from the wall W to pass at a favorable angle through the transparent band B. The most important part of the design, however, is to so proportion B and to so locate it with reference to L that the direct light will fall at the desired diagonally downward angle, thus illuminating the ground at some distance from the lamp.

Having thus described my invention what I claim and desire to secure by Letters Patent is—

1. A globe for street lighting translucent over the greater portion of its surface and having a relatively transparent band of relatively narrow width extending throughout more than half of its circumference, said band being positioned with its center line below the position of a source of light in the globe.

2. A globe for street lighting translucent over the greater portion of its surface and having a relatively transparent band of relatively narrow width extending throughout more than half of its circumference, said band subtending an angle with respect to a source of light in said globe which extends from substantially 10 degrees to substantially 25 degrees below the horizontal.

3. In construction of the class described, in combination, a source of light, a globe about said source of light having upper and lower translucent portions, both visible in a horizontal direction, and a relatively transparent band of relatively narrow width between said translucent portions and extending below said source of light, whereby said band is exposed against a translucent background and the rays emitted there-

through are augmented by those diffused by said translucent portions.

4. In construction of the class described, in combination, a source of light, and a globe positioned about said source of light having upper and lower translucent portions visible from all sides and provided with a relatively transparent band extending throughout more than half its circumference and positioned to transmit a hollow cone of rays from said source of light, the uppermost of which are at an angle of less than 45 degrees with the horizontal.

5. In a translucent globe for street lighting in combination a transparent belt below the center of the globe and a doubly frosted belt around the upper part of the globe.

6. In a translucent globe for street lighting frosted on the inside, a relatively narrow transparent belt below the center of the globe but located nearer to the middle than to the bottom of the globe, and an additionally frosted band of less than one third of the height of the globe around the exterior of the upper portion of the globe.

7. A translucent globe for street lighting of uniform opacity throughout except for a horizontal band of less opacity near its middle and a wider horizontal band of increased opacity near its upper margin.

Signed at New York in the county of New York and State of New York this 21st day of March A. D. 1914.
